No. 811,371.

PATENTED JAN. 30, 1906.

I. R. BURKHOLDER.

GATE.

APPLICATION FILED AUG. 29, 1905.

UNITED STATES PATENT OFFICE.

ISAAC RUPP BURKHOLDER, OF DAYTON, OHIO, ASSIGNOR OF ONE-HALF
TO CHARLES N. HEIST, OF CISSNAPARK, ILLINOIS.

GATE.

No. 811,371.

Specification of Letters Patent.

Patented Jan. 30, 1906.

Application filed August 29, 1905. Serial No. 276,200.

To all whom it may concern:

Be it known that I, ISAAC RUPP BURKHOLDER, a citizen of the United States, and a resident of Dayton, in the county of Montgomery and State of Ohio, have invented a new and Improved Gate, of which the following is a full, clear, and exact description.

My invention relates particularly to driveway-gates of that class which can be opened 10 at one side from a vehicle and closed in like manner at the opposite side after having passed through the gateway.

The purpose of the invention is particularly to provide a special construction of 15 hinge, through the medium of which and its connected chains or cables the gate may be freed from its latch and easily and conveniently swung to an open position and returned to a closed position.

20 Another purpose of the invention is to provide a gate especially adapted for use in connection with the hinge referred to, said gate being provided with means for raising and lowering it to a greater or lesser extent at its 25 free end.

The invention consists in the novel construction and combination of the several parts, as will be hereinafter fully set forth, and pointed out in the claims.

30 Reference is to be had to the accompanying drawings, forming a part of this specification, in which similar characters of reference indicate corresponding parts in all the figures.

Figure 1 is a perspective view of the 35 proved gate mounted and closed, a portion of the main keeper-post being broken away, the gate being shown by dotted lines in the position it assumes just after having been released from its latch for opening or closing.

40 Fig. 2 is a vertical section through the upper portion of the swing-post, a sectional side elevation of the hinge at that point, and a side elevation of the upper swing-corner of the gate; and Fig. 3 is a vertical section through 45 the lower portion of the swing-post, the lower swing-corner of the gate, and the hinge at that point.

A represents a swing-post for the gate B, C the main keeper-post, and D an auxiliary 50 keeper-post at one side of the swing-post A. D' represents a second auxiliary keeper-post, located at the opposite side of the said swing-post, as is shown in Fig. 1.

A keeper 10 is secured to the inner face of

the main keeper-post C, which keeper faces 55 the free end of the gate B. This keeper is provided with a central recess 11 in its front edge, and the said front edge is beveled or curved from the ends of the said keeper to said recess 11. Each of the auxiliary keeper-posts D and D' is provided with a catch 12, and these catches extend outward from a side portion of the post, to which they are attached, and are provided at their inner faces with recesses 13. The outer end portions of said 60 keepers 12 at their inner faces are inclined or curved in direction of the aforesaid recesses 13.

A spring-latch 14 in the form of a strap-spring is secured at its upper end to the upright 18 at the free end of the gate, and said spring is limited in its outward movement by a staple 15, which straddles it, and that portion of the spring-latch below the said staple 15 is outwardly arched at its free end, so that 70 as the gate closes on a keeper attached to any of the keeper-posts the lower portion of the spring-latch will be compressed or forced inward as it rides over the curved or inclined portion of the keeper; but the moment the 75 recess in the keeper is reached the lower end of the spring will automatically spring into said recess to hold the gate either opened or closed, as may be required.

The upper hinge b of the gate, or that member of the hinge which is carried by the gate, consists of a rod 16, which is loosely passed through an upright 17 adjacent to the swing-post A, and this rod 16 at its outer end is bent vertically downward, forming a pivot 16^a. 80 The said rod 16 is carried the full length of the gate and out through the upright 18 at the free end of the gate, and this outer end portion of the hinged rod 16 is exteriorly threaded to receive a nut 19, as shown in Fig. 90 1, whereby the pivot-point 16^a can be adjusted in or out, as occasion may demand. The said hinge-rod serves materially to strengthen the gate.

The lower hinge b', which is carried by the 100 gate, is shown in detail in Fig. 3, and it consists of an exteriorly-threaded bar 20, which is loosely passed through an aperture 21 in the rear or inner standard 17, and an adjusting-nut 22 is mounted on the threaded portion of the rod 20 outside of said standard 17. A lock-nut 23 is located on the same rod at 105 the inside of the said standard, so that the

bar 20 may be made to extend as far outward and inward as its length will permit and be held in adjusted position. The said threaded rod 20 terminates at its outer end in an eye 24, having quite a large opening. The opening of the eye is preferably wider at the top than at the bottom, the said eye 24 of the rod 20 being adapted to receive a pivot-pin 25, secured to a bracket 26, which bracket is attached to the swing-post A. The pivot point or pintle 25 is of much less diameter than the interior diameter of the eye 24 and extends in an upward direction, so that when the hinge b' is in engagement with the pintle 25 the lower portion of the gate may rock more or less thereon in a vertical direction.

The upper hinge, which is carried by the swing-post A, represents the principal feature of the invention and is clearly shown in Figs. 1 and 2. In the construction of this hinge a shaft E is provided, the upper portion 27 of which is circular in cross-section, and the lower portion 28 is rectangular or polygonal in cross-section. In the lower end of the 25 rectangular or polygonal section 28 of the said shaft E a circular vertical recess 29 is produced, and at the upper end of the shaft E it is reduced, is rendered polygonal, and is made tapering, forming thereby a bearing-point 30, the taper of which point is downward and outward. About centrally between the top and bottom of the polygonal section 28 of said shaft E a horizontal lug 29^a is formed upon its front face, or that surface 30 which faces the inner upright 17 of the gate. This lug 29^a is provided, preferably, with two or more apertures 29^b, and either one of said apertures is adapted to receive the downwardly-extending pintle-section 16^a of the 40 hinge-rod 16 of the gate. The upper portion of the shaft E is held to turn in an aperture 31, produced in a bracket 32, suitably secured to the inner face of the swing-post A, and a pintle 33 extends into the aperture 29 45 at the bottom of said shaft E. Said pintle 33 constitutes a portion of a second bracket 34, also secured to the inner face of the swing-post A.

In connection with the shaft E a sweep or 50 crown-piece E' is provided. This sweep or crown-piece E' is of skeleton segmental construction and comprises a hub 35, having a downwardly-tapered polygonal opening therein to receive the bearing-point 30 on the shaft E, so that said hub-section 35 wedges itself on the said shaft. Side arms 36 extend from opposite ends of the hub-section 35, and the said side arms extend upwardly and outwardly from said hub-section for a portion of 55 their length, their outer end portions being practically straight, and such portions are integral with or are attached to a horizontal curved bar 37, which is practically a guide-bar. On the outer face of this curved guide-bar 37, the outer face whereof is convexed, a

series of guide-fingers 38 is secured, which fingers extend above and below the said bar 37 and have their outer faces concaved.

An operating cable, rope, or chain 39 is suitably attached to the left-hand end of the curved bar-section 37 of the sweep or crown-piece E' and is carried in engagement with the said guides 38 to the right-hand auxiliary keeper-post D and through a guide-aperture in the forwardly-extending member 13^a of a 75 bracket 13, secured at the upper end of the said keeper-post D, and at the free end of the cable 39 a handle 40 is secured, which serves also as a weight. A second rope, cable, or chain 41 is attached to the right-hand end of 80 the curved bar-section 37 of the sweep or crown-piece E' and is carried to the left in engagement with the guide-fingers 38 and is passed through the forwardly-extending member 13^b of a bracket 13^c, secured to the 85 upper end of the left-hand auxiliary post D', as is shown in Fig. 1, and at the free end of this latter cable 41 a handle 42 is secured, which likewise serves as a weight.

The gate being closed, as is shown by full 90 lines in Fig. 1, as the gate is approached the right-hand cable 39 is drawn upon, whereupon the sweep or crown-piece E' is turned to the right, carrying the lug 29^a to the left, twisting the gate in that direction, as shown 95 by dotted lines in Fig. 1, and causing the gate to lean more or less to the left, at the same time freeing the latch 14 from the keeper 10 on the main keeper-post C. Upon further drawing on the cable 39 the gate will be 100 swung to the left and will engage with the keeper 12 on the left-hand auxiliary keeper-post D'. After passing through the gateway should it be desired to close the gate this is 105 done by drawing down upon the left-hand cable 41, whereupon the sweep or crown-piece is turned to the left, carrying the lug 29^a to the right and inclining the gate in that direction and releasing it from the keeper of the post D', and when the cable 41 is released the 110 gate will swing to its normal position and be brought again in locking engagement with the keeper 10 on the main keeper-post C.

It will be observed that the gate is operated almost entirely through the medium of 115 the shaft E and the sweep or crown-piece E', which first twists the gate at its hinged end in the direction that it is to swing, since it gives an inclination in that direction and then lifts the latch of the gate from its keeper, permitting the gate to be carried to open or to closed position as the sweep or crown-piece is further turned.

Having thus described my invention, I claim as new and desire to secure by Letters 125 Patent—

1. The combination with a gate, a pintle member located at the upper portion of the inner upright of the gate and an eyebolt extending from the lower portion of the same 130

upright, of a swing-post provided with a pintle at its lower portion adapted to enter the said eyebolt of the gate, brackets secured to the upper portion of the swing-post, one bracket being provided with an upwardly-extending pintle and the other bracket with an aperture, a shaft passed through the said aperture in the said bracket, which shaft has an aperture in its lower end to receive the said pintle of the other bracket, a lug extending out from the shaft, apertured to receive the hinge-pintle of the gate, a sweep or crown-piece attached to the upper portion of the shaft and of segmental formation, provided at its outer or convexed portion with transverse fingers having their outer faces concaved, and operating-ropes for the gate attached to opposite ends of the convexed outer portion of the sweep and extending in opposite directions in engagement with said fingers, and guides for said operating-ropes.

2. A gate provided with a hinge-rod pass-

ing loosely through its forward and its rearward end uprights, the forward end of the said hinge-rod being threaded, and the rear end being downwardly bent to form a pintle, an adjusting-nut at the threaded end of the said hinge-rod, a shaft having an apertured lug for engaging the pintle, upper and lower bearings for the shaft, a crown-piece or sweep carried by the shaft, guide-fingers located upon the semicircular section of the sweep, operating-ropes for the gate attached to opposite ends of the sweep, an eye secured to the lower part of the rear end upright, and a pintle engaging the eye.

In testimony whereof I have signed my name to this specification in the presence of two subscribing witnesses.

ISAAC RUPP BURKHOLDER.
